(57) **CLAIM**

The ornamental design for a travel packing bottle, as shown and described.

DESCRIPTION

FIG. 1 is a front elevational view of a travel packing bottle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a bottom, front and left side perspective view thereof;

FIG. 8 is a top, rear and left side perspective view thereof; and,

FIG. 9 is a top, front and right side perspective view thereof. The broken lines in the drawings depict portions of the travel packing bottle that form no part of the claimed design.
